CLAIM

The ornamental design for a wearable blanket, as shown and described.

DESCRIPTION

FIG. 1 is a front, top perspective view of a wearable blanket, showing my new design in a wearable configuration;
FIG. 2 is a rear, bottom perspective view thereof;
FIG. 3 is a bottom perspective view thereof;
FIG. 4 is a front elevational view thereof;
FIG. 5 is a rear elevational view thereof;
FIG. 6 is a left side view thereof;
FIG. 7 is a right side view thereof;
FIG. 8 is a top plan view thereof;
FIG. 9 is a bottom plan view thereof;
FIG. 10 is a front, top perspective view of the wearable blanket in a stored configuration;
FIG. 11 is a rear, bottom perspective view of the wearable blanket in a stored configuration.

FIG. 12 is an enlarged view of detail 12 in FIG. 6; and,
FIG. 13 is an enlarged view of detail 13 in FIG. 8.

The dashed broken lines in the figures are for the purposes of illustrating portions of the wearable blanket that form no part of the claimed design.

The short-short-long dashed broken lines immediately adjacent to the claim area in FIG. 3 and FIG. 9 are for the purposes of illustrating the boundaries of the wearable blanket, and form no part of the claimed design.

The dash-dot-dash broken lines are for notating enlarged views and form no part of the claimed design.

1 Claim, 12 Drawing Sheets
